UNITED STATES PATENT OFFICE.

WILLIAM O. MEISSNER, OF CHICAGO, ILLINOIS, ASSIGNOR TO STERLING DEVICES COMPANY, OF CHICAGO, ILLINOIS, A CORPORATION OF ILLINOIS.

NONSET STOP FOR PHONOGRAHS.

1,419,164.

Specification of Letters Patent. Patented June 13, 1922.

Application filed February 28, 1921. Serial No. 448,411.

To all whom it may concern:

Be it known that I, WILLIAM O. MEISSNER, a citizen of the United States, residing at Chicago, in the county of Cook and State 5 of Illinois, have invented certain new and useful Improvements in Nonset Stops for Phonographs, of which the following is a specification.

My invention relates to phonographs and 10 comprises a stop for terminating the travel of the record when the stylus reaches the end of the sound groove.

The main object of my invention is to stop the travel of the table by the cessation 15 of stylus travel across the record and independently of the distance actually traveled thereby.

Another object of my invention is to secure automatic operation of the stop mechanism without special attention when a record is started.

As I attain the main object mentioned by 20 means of a mechanism which is actuated by the transverse movement of the tone arm, and as such movement results from the feeding of the stylus by the spiral sound groove, which is very delicate, an additional 25 object of my invention is to provide mechanism which offers minimum resistance to the movement of the tone arm.

An additional object of my invention is to combine my automatic stop mechanism with the manually controlled stop usually 30 provided adjacent the record turn table so that the former functions through the latter and only one stop need be released when the phonograph is to be operated.

In the accompanying drawings which illustrate a preferred embodiment of my invention—

Fig. 1 is a top view of my device assembled with the tone arm of a phonograph, and showing a part of the phonograph motor and turn table with a record on the 45 latter.

Fig. 2 is a front elevation of my device attached to the tone arm.

Fig. 3 is an enlarged top view of my device showing its main operating parts in a 50 different position from that indicated in Fig. 1, and

Fig. 4 is a view and section taken on line 4—4 of Fig. 3.

In these drawings the phonograph motor

is indicated at 2, the motor board at 1, the 55 turn table at 3, and the tone arm at 4 with its base mounted on board 1. The tone arm is equipped with a reproducer 6, having the stylus 7. The above mentioned parts are of usual construction and operate in the 60 usual manner. As the record is played, the stylus 7 and tone arm move from right to left across the record.

My stopping mechanism consists, briefly, in a spring operated brake shoe 8, tending 65 to engage the edge of the record table, but held in disengaged position, during playing of the record, by a catch adapted to be released by a device which will function when the tone arm ceases to move from 70 right to left. The energy which operates this mechanism is provided by the movement of the tone arm and is stored during such movement and is released when the movement ceases.

The brake head is provided with a rearwardly extending bar 9 the lower portion of which has a downwardly extending pin 10. A horizontal plate 11 is pivotally mounted on motor board 1 by means of a 80 flat spring 12, which tends to raise the free end of plate 11. The latter end of the plate is provided with a separate piece 10^a having an opening 13 adapted to receive and retain pin 10 when the latter is moved with 85 bar 9 and brake 8 to the inoperative position of the brake indicated in Figs. 1 and 2.

Adjacent brake 8 is a vertical shaft 14 which pivotally supports a horizontal arm 15, the outer end of which forms a sleeve 90 16 for a cylindrical weight 17 having a sliding fit in the sleeve. A spring 18 has one end secured to the side of lever 15, extends therefrom toward shaft 14 and is there bent to extend outwardly past and 95 adjacent pin 17 but tending to move away from the latter. Frictional contact of the free end of spring 18 with weight 17 will hold the latter in suspended position in sleeve 16. This contact is provided by pressure applied through a pin 19 on one end of a rod 20, the other end of which is pivoted on a bracket 21 mounted on tone arm 4. Pin 19 extends through a hole in arm 15 which is large enough to permit some relative movement between arm 15 and rod 20.

The tendency of spring 18, when compressed, is to move arm 15 to the left and

thus free weight 17 from its frictional engagement but this tendency is resisted by the frictional contact between arm 15 and a collar 22 secured to shaft 14. This frictional contact is provided by a coil spring 23, the pressure of which may be accurately controlled by a nut 24 screwed on the upper threaded portion of shaft 14 and having a locking device here shown as a screw 25. 5 While shaft 14 may be frictionally driven by arm 15 to rotate in a clock-wise direction, the speed of its rotation is limited by a train of gears 26 terminating in an escapement device 27. The speed of the shaft 10 permitted by this mechanism is less than that which would be caused by the tone arm induced movement of arm 15 if the latter were pinned to shaft 14. Thus pin 19 is always pressing spring 18 against weight 15 during the movement of the tone arm. 20

When the tone arm ceases to move from right to left the energy stored in spring 18 continues to move arm 15 to the left until pin 19 engages the outer edge of the hole in arm 15. But as soon as this movement starts, spring 18 will be moved away from weight 17 and the latter will drop onto plate 11 forcing the plate downwardly and disengaging pin 10, permitting the brake spring 30 9^a to set the brake and stop the record table.

An inclined plate 28 is mounted on the mechanism base plate in the path of travel of sleeve 16 and weight 17. When the tone arm is moved from left to right weight 17 35 rides up inclined plate 28 and remains on the upper portion thereof during the initial playing movement of the tone arm during which time it is frictionally engaged by spring 18 and consequently held in raised 40 position after movement of the tone arm carries arm 15 and weight 17 beyond the upper portion of inclined plate 28. When brake shoe 8 is retracted by manual movement of finger 29 on the brake head, hole 45 13 automatically catches pin 10. It is therefore apparent that my stop will function without any attention as the various parts assume their necessary positions automatically when a person performs the customary 50 actions required for playing a record.

When my invention is properly made, the resistance of spring 18 is very small and the friction between arm 15 and collar 22 exceeds the resistance of spring 18 very 55 slightly. The connection of bar 20 to tone arm 4 near the base of the latter affords the record grooves a considerable leverage in feeding the stylus and tone arm across the record and in practice, the resistance to the 60 tone arm movement is scarcely perceptible.

The mechanism illustrated will be provided with a suitable housing and if my invention forms part of the standard equipment of a machine, its housing may form an 65 integral part of the tone arm base. The

particular form of housing, however, forms no part of my invention and is not shown or claimed.

It is a growing practice to operate phonographs by electricity and it is obvious that 70 in installing my invention on a phonograph so operated, the movement of arm 9 may serve to open and close a switch instead of moving a brake shoe to and from a moving element. 75

I am aware that changes in the form and construction of parts and details of construction may be made without departing from the invention or sacrificing the advantages thereof and I reserve the right to make 80 all such changes and modifications as fairly fall within the scope of the following claims. 85

I claim:

1. The combination of the tone arm and motor brake of a phonograph, with spring 85 mechanism adapted to receive and store energy from the movement of the tone arm while a record is being played and to expend the stored energy, upon the cessation of tone arm movement, to set the motor brake. 90

2. The combination of the tone arm and motor of a phonograph with an energy storing device comprising a compressible spring, means whereby the tone arm, while moving, stores energy in said device and prevents release of such stored energy, and mechanism operable by release of such stored energy to stop the operation of the motor. 95

3. In a phonograph, a record turn table, a brake therefor, an element for applying said brake to said table, a device for holding said brake to said table, a device for holding said element inoperative, a tone arm, and mechanism energized by movement of said tone arm to function, after movement of 100 said tone arm ceases, to release said element from said device. 105

4. The combination of the tone arm and turn table of a phonograph, with an energy storing device operated by movement of the tone arm, a turn table brake, an element holding said brake inoperative and means actuated by the energy stored in said device for releasing said brake from said element. 110

5. The combination of the tone arm and turn table of a phonograph, with an energy storing device operated by movement of the tone arm, a turn table brake, an element holding said brake inoperative and means actuated by the energy stored in said device for 115 releasing said brake from said element upon cessation of the tone arm movement. 120

6. The combination of the tone arm and turn table of a phonograph, with an energy storing device operated by movement of the tone arm, a turn table brake, an element holding said brake inoperative and means operable by said device for releasing said brake from said element. 125

7. In a phonograph stop, a turn table 130

brake, an element holding said brake inoperative, a pivoted arm, an energy storing device on said arm, mechanism operable by energy stored in said device to move said arm, 5 mechanism actuated by such movement of said arm to release said brake from said element, and means whereby energy is stored in said arm by movement of a phonograph tone arm.

10 8. A phonograph non-set stop comprising a brake adapted to stop a record turn table, a catch adapted to render said brake inoperative, a weight, a member, movable by a tone arm and adapted to suspend said weight 15 above said catch while being so moved and to drop said weight upon said catch to release said brake from said catch when otherwise moved, and means for moving said member independently of a tone arm.

20 9. A phonograph non-set stop comprising a brake adapted to stop a record turn table, a catch adapted to render said brake inoperative, a weight, a member movable by a tone arm and adapted to suspend said weight 25 above said catch while being so moved and to drop said weight upon said catch to release said brake from said catch when otherwise moved, and means energized by movement of a tone arm.

30 10. The combination with a phonograph turn table and a tone arm, of a turn table brake, a catch preventing application of said brake, an element adapted to release said brake from said catch, a member adapted, 35 when moved by the tone arm, to render said element inoperative but not so adapted when moved otherwise, a connection for moving said member by said tone arm, and other means for moving said member.

40 11. In a phonograph stop, a second turn table brake, a brake restraining element, a compressible spring, a device whereby the phonograph tone arm may compress said spring, a member, adapted to release said 45 brake from said element, held in inoperative position by said spring when the latter is

compressed, and means providing for the expansion of said spring when playing travel of the phonograph tone arm ceases.

12. In a phonograph stop, a second turn 50 table brake, a brake restraining element, a compressible spring, means whereby a tone arm during its playing travel may compress said spring, a weight held in suspended position by said spring when the latter is compressed, means adapted to permit expansion of said spring when playing travel of the tone arm ceases, said weight, when released from said spring, being adapted to render said element inoperative. 55

13. In a phonograph stop, a turn table brake, a brake restraining element, a pivoted lever, means carried by said lever adapted to release said brake from said element, a spring carried by said lever which, when compressed, holds said means inoperative and tends to move said lever upon its pivot, a member adapted to be moved by a tone arm to compress said spring, and mechanism operated by the movement of said lever to store 70 energy which continues the movement of said lever after movement thereof by said member ceases and thereby releases said means from said spring.

14. In a phonograph non-set stop, in combination with the pivoted tone arm of a phonograph, a member pivoted similarly to the pivoting of the tone arm, a connection between said member and the tone arm so that movement of the tone arm moves said 80 member, a weight mounted to slide vertically on said member, an inclined track adapted to raise said weight when said tone arm moves said member in one direction, an element on said member adapted to hold said weight in 85 raised position while said tone arm is moving said member in the opposite direction and to release said weight when said tone arm ceases to function, and means actuated by release of said weight for stopping the 90 phonograph.

WILLIAM O. MEISSNER.
